UNITED STATES PATENT OFFICE

108,763

DESIGN FOR A DRESS ENSEMBLE

Theresa Fritz, Hoboken, N. J.

Application February 9, 1938, Serial No. 74,975

Term of patent 3½ years

To all whom it may concern:

Be it known that I, Theresa Fritz, a citizen of the United States of America, residing in the city of Hoboken, county of Hudson, and State of New Jersey, have invented a new, original, and ornamental Design for Dress Ensemble, of which the following is a specification, reference being had to the accompanying drawing, forming part thereof.

Fig. 1 is a front view of a dress ensemble showing my new design.

Fig. 2 is a rear view thereof.

Fig. 3 is a fragmentary view of the front dress member of the dress ensemble.

Fig. 4 is a rear view of Fig. 3.

I claim:

The ornamental design for a dress ensemble substantially as shown.

THERESA FRITZ.
